LIQUID DISPENSING APPARATUS

Ross E. Risser, Benham, Tex.

Application November 2, 1936, Serial No. 108,713

6 Claims. (Cl. 221—95)

This invention relates to new and useful improvements in liquid dispensing apparatus.

One object of the invention is to provide an improved apparatus, particularly adapted for use with the usual liquid dispenser for relieving the pressure which has formed in the dispensing system due to vaporization or thermal expansion of the liquid.

An important object of the invention is to provide improved means operating at or near the highest point in a closed liquid dispensing system, whereby abnormal pressure which may develop due to vaporization or thermal expansion of the liquid in said system, is relieved; thereby eliminating the possibility of such abnormal pressure emptying the lines of said system by forcing the liquid therefrom.

Another object of the invention is to provide an improved pressure relief apparatus for the usual liquid dispensing system, which is arranged to remain closed during the normal operation of the dispenser and is adapted to automatically open when the pressure resulting from vaporization and also from the thermal expansion of the liquid, reaches a predetermined point.

A further object of the invention is to provide an improved pressure relief apparatus, which is connected in the system of an ordinary liquid dispenser, at or near the highest point thereof, said apparatus having an outlet which is so arranged that any vapor passing through the apparatus may escape to atmosphere, while any liquid which is forced through the apparatus by an abnormal pressure is conducted back into the system.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a view partly in vertical section and partly in elevation of an ordinary gasoline dispensing pump, having a relief valve, constructed in accordance with the invention connected therein.

Figure 2 is a horizontal, cross-sectional view, taken on the line 2—2 of Figure 1.

Figure 3 is an enlarged, transverse, vertical, sectional view, taken on the line 3—3 of Figure 2 and showing the side of the valve opposite that shown in Figure 1.

Figure 4 is a vertical, sectional view, taken on the line 4—4 of Figure 3,

Figure 5 is an enlarged, sectional view of the valve,

Figure 6 is an enlarged, detail view of the usual check and relief valve,

Figure 7 is an elevation of the upper end of another form of gasoline pump, having the invention applied thereto, and

Figure 8 is an enlarged elevation of the visi- 10 gauge of this pump and showing the vapor relief valve connected thereto.

In the drawings, the numeral 10 designates the casing or shell of an ordinary gasoline dispenser. The shell encloses the entire pumping 15 and metering mechanism, being mounted on a suitable base 11. The particular mechanism of the dispenser forms no part of the present invention and, therefore, is subject to variation.

For purposes of illustration, the dispenser is 20 shown as including the vertical line 12 which has its lower end leading from the suction pump (not shown), which draws the gasoline from the usual storage tank, while the upper end of said line is connected to the lower end of the air separator 25

13. The usual air eliminator 14 is mounted above the separator and has a vent tube 14' leading from its upper end, as will be explained. From the separator, the gasoline flows through the elbow 15' and upwardly through a vertical line 30

15. From the upper end of the line 15, the gasoline is conducted by suitable elbows and pipes 16 through the usual visigauges 17 (Figure 2) and finally to a laterally extending pipe 18, which pipe has its outer end projecting through the wall 35

of the shell or casing 10. This projecting end has the usual elbow 19, to which one end of the discharge hose 20 is secured. The opposite end of the hose is provided with the usual control valve 21 and discharge nozzle 22, the nozzle being adapted to be inserted in the usual inclined, cylindrical nozzle boot or sleeve 23 when the hose is not in use.

A check valve 24 is connected in the vertical line 15 near the lower end thereof and this valve 45 is arranged to permit an upward flow, but not a downward flow through said line. Incorporated in the check valve 24 is a pressure relief valve 25 so that in the event that the pressure between the valve 24 and the discharge hose becomes 50 excessive, this relief valve opens to permit the gasoline in the lines thereabove to flow back to the separator.

As above described, it is obvious that the gasoline is pumped into the separator 13, through 55

an elbow 15', line 15, past the valve 24 which is unseated upwardly, through the elbows and pipes 16, visigauges 17, and finally through the pipe 18 to the discharge hose 20. As soon as the dispensing of the gasoline is stopped and the control valve 21 at the nozzle 22 cut off, the check valve 24 is seated to trap gasoline in the system between said valve 24 and the nozzle. This gasoline cannot escape unless the pressure becomes excessive above the pressure relief valve 25, at which time the valve is forced open and the gasoline forced back into the separator. The above parts are all of the usual construction and are, therefore, subject to variation.

15 It has been found that pressure is formed by vaporization due to high atmospheric temperatures and also by thermal expansion of the gasoline which is trapped in the system between the check valve 24 and discharge nozzle. This 20 pressure is, of course, built up when the pump is not operating and the vapor rises to the highest point of the lines in which it is trapped, such point being adjacent the elbow 19 to which the hose 20 is attached. The pressure continues to 25 build up in the elbows and pipes 16, line 15 and hose 20. If the control valve 21 at the nozzle holds, then the pressure relief valve 25 is opened. Many times, however, the excessive pressure causes the control valve 21 to leak.

30 The opening of the relief valve 25 causes the pressure to force the gasoline from the piping 16 and visigauges 17 downwardly through the line 15 and back to the separator 13. From the separator, the liquid is forced into the eliminator 14 and through the vent tube 14' thereof. The outer end of the tube 14' is vented to atmosphere, whereby the gasoline forced from the system is wasted, running down the exterior surface of the shell 10 and creating a fire hazard. Eventually, the pressure will entirely empty the visigauges 17 and line 15. Further, the excessive pressure against the hose 20 and control valve 21 is undesirable. Thus, it will be seen that the relief valve 25 will relieve abnormal or excessive 45 pressure, but due to its location, is disadvantageous because it not only permits the system to be emptied of gasoline, but also permits a waste of gasoline.

For relieving the pressure of the vapor trapped 50 between the hose 20 and check valve 24, a vapor relief valve 30 is connected in the lateral pipe 18 and is substituted for the usual relief valve 25, which is eliminated from the valve 24. The valve 30 is preferably mounted at the outer end 55 of said pipe, being located just within the shell or casing 10. The valve includes a valve body 31 (Figure 5) which has its upper end curved upwardly at its central portion, as shown at 31', whereby this portion is in a plane above the pipe 60 18 and elbow 19. A collar 32 is formed at the lower end of the valve and this collar is internally screw-threaded. An elongate sleeve 33 is inserted through the collar to extend vertically within the valve body, the lower portion 33' of 65 said sleeve being externally threaded so as to screw into the collar 32.

The upper end of the sleeve 33 is closed except for a reduced axial port or opening 34. A conical valve member 35 is located within the 70 sleeve and is adapted to engage in the opening 34 to control the same. The member is normally held in its seated position by a coiled spring 36 which is mounted within the bore of the sleeve, being confined between the lower end of the member 35 and a plug 37 which is threaded into

the lower end of the bore of said sleeve. The plug is formed with an axial bore or opening 38, which extends entirely therethrough, whereby communication between the bore of the sleeve above the plug and that portion of the bore of 5 said sleeve below the plug, is established.

The extreme lower end of the sleeve 33 is formed with an enlarged head 39 provided with internal screw threads for receiving one end of an elbow 40 (Figure 3). The other end of the 10 elbow is connected to the upper end of a vertical conductor 41, which has its lower end connected to the upper end of and depending downwardly through the vertical leg of a T connection 42 (Figure 4). The opposite end of said leg is connected to the upper end of the vent tube 14' of 15 the air eliminator, and the conductor 41 is of sufficient length to extend axially within the upper portion of the tube 14'. It is noted that both the tube and T have a greater diameter 20 than the conductor, as clearly shown in Figure 4.

The lateral leg 42' of the T is connected to an opening 43 which is provided in the side of the nozzle boot or sleeve 23, which boot is open to the atmosphere. A suitable screen 44 covers 25 the opening 43 to prevent dirt and other extraneous matter, entering the T 42 and tube 14'. With this arrangement, it will be seen that air rising from the air eliminator 14 may pass through the tube 14', upwardly around the lower 30 end of the conductor 41 and outwardly to atmosphere from the T connection 42 through the boot or sleeve 23. Vapor passing downwardly through the conductor 41 is released from the lower end thereof into the upper end of the tube 35 14', from which it escapes to the atmosphere through the T 42 and boot 23. Any gasoline which may escape through the conductor will, of course, drop downwardly into the eliminator 40 14, from where it can be conducted by a return line 45 (Figure 1) back to the suction pump (not shown).

During the normal operation of the dispensing pump, the valve member 34 remains in its seated position, because the pressure of the coiled 45 spring 36 is sufficient to resist this pump pressure. Therefore, the valve 30 is inoperative during the normal operation of the pump and does not in any way interfere with the dispensing of the gasoline, said gasoline passing around the 50 sleeve 33 and out through the hose 20. When the pump is not operating, the nozzle 22 is placed within the nozzle boot or sleeve 23, the outer end of the hose being supported by the usual bracket 18' provided for this purpose. At this 55 time, as has been explained, the control valve 21 at the nozzle and the check valve 24, are closed, whereby gasoline is trapped therebetween.

When the atmospheric temperature is sufficiently high, vaporization of the gasoline occurs 60 and the vapor will, of course, rise to the highest point in the lines wherein said gasoline is trapped. This highest point is the upwardly extended top of the valve body 31 adjacent the valve member 35. The vaporization, together 65 with the thermal expansion of the gasoline, will build up a pressure in the lines between the nozzle valve 21 and check valve 24, and when a pre-determined pressure in the valve body 31 is 70 reached, the valve member 35 is moved downwardly under tension of the spring 36, whereby the axial opening 34 in the sleeve 33 is uncovered and the pressure relieved. Any vapor which may have formed is permitted to escape down- 75

wardly through the bore sleeve 33, port 38 in the plug 37, and into the conductor 41. As has been explained, the vapor released from the lower open end of the conductor rises into the 5 T 42, from where it escapes to atmosphere through the screened opening 43 and boot 42. Any gasoline which is expelled through the sleeve 33 merely falls from the conductor 41 into the vent tube 14' and is thereby conducted to the 10 eliminator 14, and then through the return 45 to the suction pump (not shown).

Therefore, it will be seen that the vapor is taken from the system at its point of accumulation and an abnormal pressure, due either to 15 vaporization or thermal expansion of the gasoline, which otherwise would entirely empty the piping 16, visigauges 17, and line 15, and result in a waste of gasoline, is prevented. It is noted that although it is preferable to mount the pressure relief valve at the highest point in that portion of the system wherein gasoline is trapped when the pump is not operating, it is not absolutely essential. So long as said valve is located sufficiently close to prevent forcing the gasoline 20 from the lines of the system, the purposes of the invention are accomplished.

In Figures 1 to 6, the invention has been shown as applied to an ordinary dispenser including the usual air eliminator and separator. Many dispensers do not have these parts and, obviously, they form no part of the invention per se. If an eliminator is not employed, then the conductor 41 could have its lower end entering any suitable tube, which would conduct the gasoline 25 entering the same back to the suction pump or the original source of supply.

The dispenser shown in Figures 1 to 6 is one wherein the visigauges 17 are located in the wall of the shell 10. In many instances only a single exterior visigauge is provided. Such a structure is shown in Figures 7 and 8, wherein an exterior visigauge 50 is substituted for the elbow 19, which is secured to the extending end of the lateral pipe 18. With this arrangement, the upper end of the visigauge 50 is the highest point of that portion of the system wherein gasoline is trapped, and, therefore, the valve 30 is preferably mounted thereabove. In this instance, the structure of the valve is exactly the same and has one end connected by an elbow 51 with the top of the gauge. The opposite end of the valve is closed by a plug 52, while the conductor 41 leads from the lower end of the valve body, as in the other form. The operation of the valve is exactly the same as hereinbefore described, the valve 30 opening when the pressure reaches a predetermined point.

What I claim and desire to secure by Letters Patent is:

60 1. As a subcombination in a liquid dispensing apparatus, a valve including, a valve body adapted to be connected in the dispensing line of a liquid dispensing apparatus, a sleeve extending vertically within the body and having its lower end extending from the body, said sleeve having a reduced opening at its upper end, and a spring-pressed valve member for controlling the flow through said opening and sleeve.

70 2. As a sub-combination in a liquid dispensing apparatus, a valve including, a valve body adapted to be connected in the dispensing line of said dispensing apparatus, a sleeve extending vertically within the body and having its lower end

extending from the body, said sleeve having a reduced opening at its upper end, and a spring-pressed valve member for controlling the flow through said opening and sleeve the member being inactive during the normal operation of the 5 dispensing pump.

3. A liquid dispensing apparatus of the character described, including, a closed dispensing line under pump pressure leading from a source of liquid supply through metering means to a valve 10 controlled discharge nozzle, a check valve in the line between the metering means and discharge nozzle for maintaining a predetermined volume of liquid in the dispensing line, and a relief valve located in said line at the highest point therein 15 between said check valve and said nozzle acting to liberate vapor and excess liquid above the normal highest liquid level in the line whereby to relieve abnormal pressure and maintain the normal volume of liquid in the line. 20

4. In a closed discharge line for a liquid dispensing apparatus of the character described, containing a predetermined volume of liquid maintained at a given normal pressure in the line, a check valve at the supply end of the line, 25 a valve controlled nozzle at the discharge end of the line, and a pressure relief valve comprising a valve body located in the highest part of the line between said check valve and valve controlled nozzle and having a hollow portion raised 30 above the highest normal liquid level of the line and an outlet tube extended upwardly in said valve body and having a restrictedly apertured end portion located in said raised hollow body portion. 35

5. A closed discharge line for a given capacity for a liquid dispensing apparatus of the character described, said line maintained filled with a measured supply of liquid to be dispensed, a check valve at the supply end of the line and a valve 40 controlled nozzle at the discharge end of the line between which the liquid is normally retained, and a pressure controlled relief valve comprising a hollow body located in the highest part of the line between said check valve and nozzle, an outlet tube extended into said body with its upper end portion provided with a minutely restricted aperture above the highest normal liquid level of the line, and a spring-pressed valve member normally closing said aperture whereby to open upon 45 pressure increase above normal and thereby liberate vapor and excess liquid so as to maintain the liquid in the line at normal volume and pressure. 50

6. A liquid dispensing apparatus of the character described having a pump and air separator, and including, a closed discharge line into which the liquid is supplied under pump pressure through the air separator, said separator having an air eliminator connected therewith and the 60 eliminator having a vent tube leading upwardly therefrom and a drain tube leading downwardly therefrom, a valve controlled nozzle at the discharge end of the line, a check valve at the supply end of the line through which the liquid is 65 passed from the air separator, and a pressure controlled relief valve located in said discharge line at the highest part thereof and between said nozzle and check valve, said relief valve having an outlet opening above the normal highest liquid level in the line and a discharge tube leading into said vent tube of the air eliminator. 70
